UNITED STATES PATENT OFFICE.

WILLIAM M. BELL, OF PORTSMOUTH, OHIO, ASSIGNOR TO WHITAKER-GLESSNER COMPANY, OF WHEELING, WEST VIRGINIA, A CORPORATION OF WEST VIRGINIA.

END CLOSURE FOR RANGE BOILERS AND LIKE CONTAINERS.

Application filed April 21, 1920. Serial No. 375,601.

To all whom it may concern:

Be it known that I, WILLIAM M. BELL, a citizen of the United States of America, and resident of Portsmouth, county of Scioto, and State of Ohio, have invented certain new and useful Improvements in End Closures for Range Boilers and like Containers, of which the following is a specification.

10 This invention relates broadly to sheet-metal containers or tanks which are subjected to internal pressure strains, and more particularly to an end closure for such containers.

15 The primary object of the invention is to provide a structurally improved form of end closure for pressure tanks, boilers, and the like, as, for instance, the usual types of domestic range boilers.

20 A further object is to provide an end structure designed particularly as a bottom for range boilers and similar containers, which possesses the requisite strength and durability, which requires a minimum of material in its formation, which provides for ready drainage without the collection of sediment, which admits of the easy application and removal of sputts as occasion may require, and which consumes a minimum quantity of spelter or other coating material.

25 With these and other objects in view, the invention resides in the features of construction which will hereinafter be fully described, reference being had to the accompanying drawings, in which—

30 Figure 1 is a plan view of an end closure constructed in accordance with the present invention, and—

35 Figure 2 is a section on line 2—2, Fig. 1, showing the closure employed as a bottom for a tank or container of range-boiler type.

40 The closure is formed of a single piece of sheet metal pressed to form a body 1 which, generally considered, is of concavo-convex form and which has a central circular opening 2 for the reception of a sput 3. Employed as a bottom closure for a cylindrical boiler body 4, as shown in Fig. 2, the concave surface of the body 1 is uppermost. Said body has an integral peripheral flange 5 extending downward vertically therefrom and adapted to fit snugly within the lower

end of the boiler body 4 and to be rigidly attached to the latter by suitable means, as by the usual rivets or by welding.

45 The body 1 is inclined from its peripheral portion inward throughout the major part of the length of its radius on a regular gradient of appropriate degree, as approximately fifteen degrees, thence inclines sharply, as at an angle of approximately forty-five degrees, throughout a distance, measured vertically, substantially equal to the thickness of the head portion 3^a of the sput 3, and thence extends horizontally to the edge of the opening 2 to form a flat ledge 6 upon which the sput-head 3^a may seat. The inclined shoulder 7 formed by the sharply inclined portion of the body meets 50 and merges with the ledge 6 at a distance from the opening 2 substantially equal to the width of the flange which constitutes the head 3^a of the sput 3, so that said head more or less closely abuts the lower portion 55 of said shoulder. Thus there is formed intermediate said shoulder 7 and the periphery of the head 3^a a substantially triangular groove or channel of such slight dimensions that the spelter or other material employed in coating the structure following assemblage of the parts finds lodgment therein and fills the same to, or approximately to, the level of said head, as shown at 8 in Fig. 2. An effective seal is 60 thus formed about the sput 3 with the use of a minimum quantity of material, and at the same time the formation of an open channel in which sediment could collect is effectively eliminated.

65 Formed in the body 1 is a plurality of radially disposed ribs 9 which are employed for reinforcing the bottom to enable it to withstand excessive pressure strains to which it is liable to be subjected when employed in a boiler or the like. Said ribs, which are formed by the press in the same operation in which the bottom is pressed into the irregular concavo-convex form hereinbefore described, are of inwardly tapering form and of substantially uniform height throughout the major part of the length thereof, but have their outer ends disappearing, or fading out, as shown at 9^a, in the horizontal plane of the highest 70 level of the bottom structure, and have their

inner ends terminating at or adjacent to the top of the inclined shoulder 7.

While the closure is herein shown and described as a bottom for containers, it is obvious that it may be employed also as a top end closure.

What I claim is—

1. An end closure for range boilers and like containers, consisting of a sheet-metal plate of concavo-convex form disposed with its concave face inward and having an outwardly extending peripheral flange adapted to fit within and to be rigidly attached to the boiler body, said plate having therein a centrally located sput-receiving opening and having formed about said opening a horizontal circular ledge adapted for having the head of a sput seat thereon, said ledge being encircled by a shoulder having a relatively sharp inclination. 70

25 to the depression whereby said ledge is formed.

2. An end closure for range boilers and like containers, consisting of a sheet-metal plate of concavo-convex form disposed with its concave face inward and having an outwardly extending peripheral flange adapted to fit within and to be rigidly attached to the boiler body, said plate having therein a central opening and having formed about said opening a horizontal circular ledge, a sput mounted in said opening with its head seated upon said ledge, said ledge being depressed to a plane located below the adjacent portion of the concave face and being joined to the latter by a sharply inclined shoulder having a height approximating the thickness of said sput-head, said shoulder and the periphery of said sput-head being separated by a channel which is of such narrow width that it is adapted to be closed by the material employed in coating the boiler, and said plate having formed therein a plurality of radial reinforcing ribs which have their inner ends terminated adjacent to said shoulder. 100

3. An end closure for range boilers and like containers, consisting of a sheet-metal plate of concavo-convex form disposed with its concave face inward and having an outwardly extending peripheral flange adapted to fit within and to be rigidly attached to the boiler body, said plate having therein a centrally located sput-receiving opening and having formed about said opening a horizontal ledge outwardly-depressed to occupy a lower level and adapted for having the head of a sput seat thereon. 115

4. An end closure for range boilers, consisting of a sheet-metal plate of concavo-convex form disposed with its concave face

inward and having an outwardly extending peripheral flange adapted to fit within and to be rigidly attached to the boiler body, said plate having therein a centrally located sput-receiving opening and having formed about said opening a horizontal circular ledge adapted for having the head of a sput seat thereon, said ledge being encircled by a shoulder having a relatively sharp inclination. 75

5. An end closure for range boilers and the like, consisting of a sheet-metal plate of concavo-convex form adapted for mounting within an end of a boiler body with its concave face inward, said plate having therein a centrally located sput-receiving opening and having formed about said opening a depressed horizontal ledge adapted for having the head of a sput seat thereon, said ledge being located below the plane of the concave face a distance approximating the thickness of the head of the sput so that the face of said head lies approximately in said plane. 80

6. An end closure for range boilers, consisting of a sheet-metal plate of concavo-convex form adapted for mounting within the end of a boiler body with its concave face inward, said plate having therein a centrally located sput-receiving opening and having formed about said opening a horizontal ledge adapted for having the head of a sput seat thereon, said ledge being depressed below the plane of the concave face a distance approximating the thickness of the head of the sput so that the face of said head lies approximately in said plane, said ledge being closely encircled by a sharply inclined shoulder, and a filling for the space intermediate said head and said shoulder. 95

7. A bottom for range boilers comprising a sheet-metal plate adapted to be mounted within the lower end of a boiler body, the body of said plate being provided with a central opening and being dished downward toward said opening to form a regularly inclined drainage surface, the portion of said body adjacent to said opening being depressed downward to form a horizontal opening-encircling ledge, and a sput disposed in said opening with its head seated upon said ledge, the head of said sput having its top surface substantially flush with the lower end portion of said drainage surface. 100

8. A bottom for range boilers comprising a sheet-metal plate adapted for mounting closely within the lower end of a boiler body, the body of said plate being provided with a central opening and being dished downward toward said opening to form a regularly inclined drainage surface, the portion of said body adjacent to said opening being depressed to form a horizontal opening-encircling ledge, a sput disposed in said opening with its head seated upon said ledge, the 115

peripheral portion of the sput-head being separated from the adjacent portion of the plate body by a narrow channel adapted to be closed by the spelter employed in coating
5 the boiler, the top face of said sput-head being substantially flush with the lower end portion of said drainage surface.

In testimony whereof, I affix my signature in presence of two subscribing witnesses.

WILLIAM M. BELL.
